WARM AIR HEATING REGISTER

Filed Dec. 29, 1927

FIG. 1.

FIG. 2

INVENTOR:
ROY G. HENDRICKS

by his atty *Carl B. Muller*

UNITED STATES PATENT OFFICE

ROY G. HENDRICKS, OF LAKEWOOD, OHIO, ASSIGNOR TO THE FOREST CITY-WALWORTH
RUN FOUNDRIES COMPANY, OF CLEVELAND, OHIO

WARM-AIR HEATING REGISTER

Application filed December 29, 1927. Serial No. 243,229.

My invention pertains to a register adapted to control circulation through an air passage such as the room outlet of an air heating conduit.

The object of my invention has been to produce a structure of the character described made entirely of stamped parts so as to be lighter in weight and more economical in large production, while attractive in appearance and convenient to assemble with quick detachability of certain units.

It is to be realized that the scope of my invention comprehends many equivalent constructions. The showing of the drawing and the particular description are merely specific exemplifications of a plurality of mechanical embodiments and arrangements.

Adverting to the drawing:

Figure 1 is a front elevation of a register embodying my invention.

Figure 2 is a side elevation thereof.

Figure 3 is a fragmentary rear elevation of the upper construction on the line 3—3 of Fig. 2 showing hinges and other details.

Figure 4 is an enlarged vertical section on line 4—4 of Figure 3.

Figure 5 is a similar view showing certain parts in a partially detached position.

Figure 6 is a correspondingly enlarged vertical section on line 6—6 of Figure 3 and with a damper in its open position.

Figure 7 is a view corresponding to Figure 6 taken on line 7—7 of Figure 3.

A main frame 1, quadrilateral as shown, is intended to be fitted in a wall of a room and has a forward face slightly receding in an upward direction and defining a quadrilateral opening 2, the lower margin of which is defined by a rearwardly recessed and inversely bent flange 3 comprising a lower substantially horizontal section provided with a pair of slots 4 and comprising an upper horizontal section 5 to serve the function of a ledge, as will be hereinafter explained. The upper margin of the opening 2 is also defined by an inversely bent flange including a horizontal section 6, a downwardly extending section 7 and another horizontally extending section 8 which is fashioned with a plurality of spaced recesses 9.

A rectangular grille 10 includes a forwardly protruding reticular forming section composed of crossed two-ply ribs 11 consequent to a stamping operation and calculated to reinforce the grille work. The lower margin 12 of the reticulated portion of the grille is fashioned as an inwardly turning flange 13 to provide crosswise extending recesses, as shown in Figure 2, the purpose of which will be hereinafter disclosed. The bottom of the grille 10 is provided with a plurality of tongues 14 corresponding in number and arrangement to the disposition of the slots 4 and adapted to be inserted therethrough, as shown in Figure 2, whereby movably and detachably to connect the lower end of the grille with the frame 1.

The upper margin 15 of the grille is flat and is secured, as, for instance, by spot welds 16 to a section 17 of a shutter and grille carrying member including also a rearwardly projecting and resilient section 18 which in conjunction with the section 17 determines the L-shape of said member. The flange 18 fashioned at intervals with upwardly offset spherical projections 19, corresponding in number and spacing to the recesses 9 and adapted to be sprung into interfitted relation therewith, as shown in Figure 4, or forcibly withdrawn, as shown in Figure 5. At four points along the flange 18 and between the section 17 and offsets 19, hinge sockets 20 are struck out in a manner well known to the stamping art. A sheet metal shutter 21, intended alternatively to lie against the inside of the grille 10, has two portions of its upper edge curled at 22 to form a pair of coacting hinge sockets. It will be observed that the hinge sockets 22 are curved inversely to the four hinge sockets 20 and adapted to be locked one between each spaced pair of hinge sockets 20, in which position they are held by hinge pins 23, as will be readily understood by those skillful in the art. The lower end 24 of the shutter is curved forwardly and is adapted to occupy a position partially underneath the flange 13 whereby to improve the closure at that point when the shutter occupies the position in which it is illustrated in Figure 4. The middle of the shutter is provided at its top with an aperture 25, shown in Figure 3. A handle 26 pro-

jects rearwardly through the middle top opening in the grille and passing through the aperture 25 is bent downwardly at 27 where it is secured to the inside of the shutter 21 in any approved manner, perhaps preferably by spot welding.

It should now be clearly understood that the shutter structure in its entirety, including the grille 10 and shutter 21, may be 10 readily inserted by first causing the tongues 14 to project through the slots 4 and then snapping the upper end into the position shown in Figures 2 and 4. The interconnection of the complementary offsets 9 and 19 15 may be readily disjoined by a sudden forward jerking upon the grille 10, the mutual yielding of the resilient flanges 8 and 18 readily permitting the sliding disengagement to the position shown in Figure 5, preparatory to a 20 subsequent lifting action which will withdraw the tongues 14 from the slots 4. A tilting action imparted to the handle 26 readily shifts the shutter 21 from its closed to its 25 open position, or vice versa and it is maintained in either position by friction.

The forward protrusion of the reticular section has required, as I believe, the exercise of invention. While a bulged lattice work has long been used in cast iron form to permit 30 the circulation through lateral apertures, I believe I am the first successfully to achieve it in a drawn steel stamping so that the ribs 11 could be as wide as 9/16 of an inch without fracturing the metal. I achieved such a 35 stamping by commencing with a blank, the four edges of which are initially bowed outwardly and then by employing a punch only 1/20 of an inch thick effecting the two-ply formation and at the same time drawing the 40 edges of the blank inwardly to four straight lines which will define a rectangular figure. I wish provisionally here to record such a successful method for which I may later file a separate patent application.

45 I claim:

1. In a register, the combination of a frame, a structure including a resilient rearwardly extending flange arranged for detachable fitting against the inner margin of 50 said frame, said flange including struck-out hinge pin sockets and a shutter including complementary hinge pin sockets.

2. In a register, the combination of a frame having a forward face defining an 55 opening and receding in an upward direction, said frame being fashioned around its interior margin with a rearwardly projecting flange, a reticulated structure provided on its lower edge with tongues passed through 60 apertures in said flange, an L-shaped member having one arm secured to the upper margin of said structure, the other arm of said member being resiliently free and adapted to interlock with said frame and a shutter 65 hinged to said resilient arm and provided

with a handle projecting forwardly both through said shutter and structure.

Signed by me this 15th day of December, 1927.

ROY G. HENDRICKS.
